UNITED STATES PATENT OFFICE.

CLIFFORD JOHNSON, OF GLEN COVE, NEW YORK.

AUTOMATIC AUTOMOBILE SIGNAL.

Application filed September 10, 1924. Serial No. 736,846.

The main object of this invention is to provide a vehicle signal which is observed in the form of a hand simulating the holding of an illuminated box-like structure on which the direction in which the vehicle is about to turn, is indicated. The device is actuated in a novel manner and by the movement of a lever which simultaneously extends the hand and at the same time illuminates that portion of the box-like structure which is to indicate the direction in which the vehicle is to turn.

This and other objects will become apparent in the description below, in which characters of reference refer to like-named parts in the drawing.

Referring briefly to the drawing, Figure 1 is a front elevational view of the device, showing the casing broken away to illustrate the interior mechanism.

Figure 2 is a longitudinal sectional elevational view, showing the interior of the casing.

Figure 3 is a top plan view of Figure 1. Figure 4 is a wiring diagram of the circuit used in illuminating the direction lamps.

Figure 5 is an enlarged cross sectional view of the indicating hand and lamp chamber mounted thereon.

Figure 6 is a fragmentary and partly sectional elevational view of the extensible signal actuating crank.

Referring in detail to the drawing, the numeral 10 indicates a rectangular casing in which the entire signaling device is mounted. The casing is provided with a bottom 11 and is open at the top, said top being covered by a flat door 12. Within the casing chamber 13 and mounted on the face of the bottom 11, is an extending bracket 14 which is provided with a hollow sleeve 15. This sleeve extends longitudinally in the casing and receives a horizontal bar 16. Said bar has a down-turned projection 17 at its forward end and the rear end is provided with an enlargement 18 in which a hole is provided. Beneath and to one side of the bracket 14, an additional bracket 19 is supported on the internal face of the bottom 11 within the chamber 13. This bracket has a pair of foot plates which secure to the bottom and raise a ledge of the bracket above said bottom. On this ledge, a pair of vertically aligned slots 20 are provided in which pins are slidably mounted. To the pins, the end of crossed bars of lazy tongs 21 are

firmly anchored. The opposite end of the lazy tongs have pins thereon which are engaged in a pair of vertical slots 22 formed in a plate 23 which simulates an outstretched hand. Said plate 22 has suspended from and supported on member 17 of the bar 16, a pin which passes thru said plate and bar being the means of securing it. A box-like structure 24 is mounted on the plate 23 and said box is divided into compartments 25 and 26 by a wall 27. In the compartment 25, a red lamp 28 is mounted and in the opposite compartment 26, a green lamp 29 is mounted. The front of the box is open and is covered by a transparent glass 30 on which the words Right and Left are engraved. The word Right covers approximately half the width of the glass and is in front of compartment 25 and the lamp 28, and the remaining word Left is formed on the glass in front of the compartment 26 and lamp 29. A vertical channel 31 extends upwardly in the plate 23 forming the outstretched hand and this channel serves as a conduit thru which the electrical current carrying wires are connected to the sockets of the lamps 28 and 29, said wires being indicated by the numeral 32. A hollow post 33 is mounted on the top of the casing 10 and on the top of this post, a pair of button terminals 34 and 35 are mounted. A shaft 36 passes vertically downward thru the post and into the chamber 13 and is rotatably mounted on its lower end in a lug 37. This post has at its upper end a lever 38 which is electrically connected to a battery 39 by a lead wire 40, the lower face of said lever being adapted to contact with the terminal buttons 34 or 35 when said lever is rotated to a position directly above either one of said buttons. Intermediate the length of the shaft 36, a stud 41 extends outwardly therefrom at right angles to the axis of the shaft and thru this stud, a circular opening 42 passes in which one end of a stem 43 is slidably mounted. The opposite end 44 of said stem is bent at right angles to the axis of the portion 43 and is mounted in the hole provided in the portion 18 of the bar 16.

The vehicle signal is used in the following manner. The device is preferably mounted by securing the casing to the dashboard at one side and in front of the driver's seat so that ready access can at all times be had to the lever 38. As the vehicle on which the device is mounted is about to turn the cor-

ner in the right hand direction, the lever 38 is rotated until it contacts with the button 34 mounted beneath the lever on the post 33. In thus rotating the lever to this position, the bar 16 is moved outwardly toward the end of the casing thru the crank movement of the portions 41, 43, and 44. The plate 23 which is cut-out similar to a hand is moved outwardly thru the slot 45 in the casing 10 and when the button 34 contacts with the lever 38, a circuit is closed thru the lamp 28, thus illuminating said lamp and providing prominence to the signal by giving an illuminated background to the word Right written in front of the chamber 25. When the vehicle is to be maneuvered in the left hand direction, the handle lever is rotated until it contacts with the button 35, thus closing the circuit thru the lamp 29 which provides an illuminated background for the word Left. In this manner the words right and left are displayed in a very prominent manner selectively, and in addition, full control of the semaphore plate 23 is also taken care of with the same movement. The extensible crank consisting of members 36, 41, and members 43 and 44, the former of which is

slidable in the stud 41 is required as the angle of movement with respect to the axis 36 is variable thruout its travel when extending or telescoping the bar 16 out of or into the casing 10.

I claim:—

A signaling apparatus comprising a casing having an opening therein, a plate member adapted to pass out of said casing thru said opening, a lazy tongs supporting said plate member, a sleeve bracket mounted in said casing, a bar slidably supported in said sleeve bracket, a shaft rotatable in said casing, a right angle extension on said shaft, an extensible stem slidable in said extension engaging the bar for extending the latter and the plate member thru the opening to a position exterior of the casing, said shaft extending above the casing, a post supporting said extending end of the shaft, a stud mounted on said shaft having a channel passing therethru, and a stem slidable in said channel and engaging said bar to permit variation of the distance between the bar and the axis of the shaft.

In testimony whereof I affix my signature.

CLIFFORD JOHNSON.
